UNITED STATES PATENT OFFICE.

CHARLES A. LANDBACK, OF PERTH AMBOY, NEW JERSEY, ASSIGNOR TO C. PARDEE WORKS, OF PERTH AMBOY, NEW JERSEY, A CORPORATION OF NEW JERSEY.

TILE PRESS.

Application filed April 13, 1922. Serial No. 552,272.

To all whom it may concern:

Be it known that I, CHARLES A. LANDBACK, a citizen of the United States, and a resident of Perth Amboy, in the county of Middlesex and State of New Jersey, have invented a new and Improved Tile Press, of which the following is a full, clear, and exact description.

This invention relates to tile presses and has for an object to provide an improved construction wherein power may be used to perform the pressing operation without endangering the workmen or the apparatus.

Another object of the invention is to provide a power tile press wherein the power will be automatically disconnected from the pressing structure when said structure has been retracted to a given position.

A still further object is to provide a power driven tile press wherein the power is turned on manually and turned off automatically, the structure being such that in case the manual operating means is released, the automatic action will function.

In the accompanying drawings—

Figure 1 is a perspective view of a press disclosing one embodiment of the invention.

Figure 2 is a front view of the structure shown in Figure 1 with certain parts shown in section for better illustrating the construction.

Referring to the accompanying drawings by numeral, 1 indicates a base or support of any kind on which a base plate 2 is mounted, said base plate being provided with up-standing columns 3 and 4 merging together at the top for forming a horizontal section 5, said horizontal section being enlarged at 6 so as to accommodate the internally threaded sleeve 7 which is bolted or otherwise rigidly secured to the section 5. A supporting platform 8 is bolted or otherwise rigidly secured to the section 5 and pressed against the columns 3 and 4 by suitable brackets 9 and 10. The platform 8 is provided with an aperture of the same size as the aperture in the enlargement 6 and accommodates a guiding sleeve 11 which has an interior bore slightly larger than the threaded shaft 12 whereby it may act as a guide for this shaft though the threads of the sleeve 11 coact with the threads of this shaft for producing a longitudinal movement of the shaft as it is rotated.

During the use of the device, the threads of sleeve 7 become more or less worn and, consequently, the shaft 12 might wobble to a slight extent and thereby cause the dies 13 carried by the reciprocating head 14 to improperly register with the openings in the mold 15. As the sleeve 11 is not provided with internal threads but merely acts as a guide, it will not wear as rapidly as the threads and, consequently, will continue to cause the shaft 12 to move in a straight line notwithstanding the worn threads in sleeve 7. It is, of course, evident that the sleeve 7 may be removed and a new one substituted at any time.

The threaded shaft 12 is rigidly secured to a power wheel 16 at the upper end while the lower end is connected in any suitable manner with the head 14 which is guided in suitable guide-ways in brackets 17. The power wheel 16 is provided with an annular friction body 18 on the periphery which may be leather or other material as preferred, said friction body 18 engaging the surfaces 19 and 20 of power disks 21 and 22 at different times, disk 21 acting as a power member to cause the shaft 12 to move downwardly while the disk 22 acts to cause the shaft 12 to move upwardly. Both of the disks 21 and 22 are rigidly secured to the power shaft 23, which power shaft carries a pulley 24 designed to receive power from any suitable source and during the operation of the machine continually rotates.

It will be noted from Figure 2 that the shaft 23 is supported by suitable brackets 25 and 26 carried by the platform 8, bracket 25 having an opening 27 for accommodating the lever 28. A sleeve 29 is loosely mounted on the reduced section 30 of shaft 23, said sleeve having a bearing sleeve 31 arranged 90 interiorly thereof and held against independent longitudinal movement by the stops 32 and 33. If desired, friction washers 34 and 35 may be arranged between the stops and the sleeve 29. The sleeve 29 is provided 95 with oppositely extending projections or pins 36 adapted to fit into the sockets 37 of the yoke 38, which yoke is preferably integral with the sleeve 39 and said sleeve in turn being preferably integral with the lever 28. By this construction and arrangement, the shaft 23 may freely rotate and by swinging the lever 28 upwardly or downwardly 100

cause a reciprocatory motion for the shaft 23. The upper end of rod 40 is pivotally connected to the end of lever 28 opposite the sleeve 39 whereby when said rod is reciprocated the lever will be rocked. Stops 41 and 42 are adjustably mounted on the rod 40, said stops if desired being merely nuts threaded onto the rod and acting as stops for the respective springs 43 and 44, said springs in turn acting against a plate 45 rigidly secured to platform 8. In this way, the rod 40 and parts associated therewith are resiliently maintained in the position shown in Figure 2. The lower end of rod 40 is pivotally connected to a hand operated lever 46 which lever is pivotally mounted on a bracket 47 secured to the column 4.

When the machine is in operation and it is desired to cause the dies 13 to move downwardly for pressing the material in mold 15, lever 46 is moved downwardly manually and spring 44 brought under tension. This movement also will act on the sleeve 29 and associated parts for shifting the power shaft 23 longitudinally and thereby causing the disk 21 to press against the friction surface 18 of power wheel 16. It will be noted that the disk 21 will contact with the surface 18 near the center at first and, consequently, a greater power will be exerted at this time though a slower motion than when the power wheel 16 is in a lower position. As the disk 21 continues to rotate and also wheel 16 continues to rotate, said wheel will be moved downwardly by reason of the action of the threads on the shaft 12. This downward movement will continue as long as the lever 46 is held down and until the dies 13 have compressed the material in mold 15. As the wheel 16 moves downwardly, the friction surface or member 18 will gradually move from the shaft 23 and, consequently, the speed of the power wheel 16 will increase. This will give a blow to the material in mold 15 and by reason of the action of the threads of shaft 12 and the slipping action of the disk 21, the dies will rebound slightly but as the disk 21 continues to rotate, the dies will again move down for a second compression though not a blowing one. As soon as this second compression has taken place, the operator releases the lever 46 whereupon the spring 44 will move the parts back to the position shown in Figure 2 and in doing so will cause the disk 21 to move away from operative engagement with member 18 and disk 22 to move over into engagement therewith. This will result in the transmission of power from disk 22 to power wheel 16 in a reverse direction and, consequently, will cause the threaded shaft 12 to move upwardly. This upward movement will continue until the friction member 18 moves off the contact surface 20 into a position opposite the hollowed section 48 which

will result in the disconnection of the power from power wheel 16 and at this same time the upper surface of the peripheral part of the wheel 16 will be brought into engagement with brakes 49 arranged on opposite sides of the wheel, said brakes being guided by U-shaped members 50 straddling shaft 23 and held resiliently in place by the posts 51 and the various springs 52.

By this construction and arrangement, whenever the machine is released either intentionally or accidentally, dies 13 will be automatically raised and also the power will be automatically cut off as well as an automatic throwing in of the brake 49. It will be noted that the springs 43 and 44 act to resiliently hold the disks 21 and 22 in their operative position when permitted to do so, so that a slipping action may occur where the resistance has reached a predetermined point.

What I claim is:—

1. In a tile press of the character described, a supporting frame structure, a mold adapted to be carried by said frame structure, a die, a head for carrying said die, means for guiding said head so that the die may be forced into the mold structure, a power member carried by the frame structure connected with said head, manually actuated means for setting said power member into operation for forcing the die into said mold, automatically actuated means for causing said power member to be moved to an inoperative position upon releasing said manually actuated means, and a brake for stopping the movement of said power member.

2. In a tile press of the character described, a rotating power wheel, a pair of driving disks, means for rotating said disks, manually actuated means for moving one disk into contact with said power wheel, automatically actuated means for moving the other disk into operative engagement with said power wheel, said opposite disk having a depression extending from the center outwardly a predetermined distance and adapted to cause a disconnection of the power wheel from the disk when the power wheel has been moved to a certain position, and a brake for stopping the rotation of said power wheel.

3. In a tile press of the character described, a power disk provided with an annular friction surface, and an annular depression adjacent said friction surface.

4. In a tile press of the character described, a power wheel having an annular friction member arranged on the periphery, a power disk co-acting with said power wheel formed with an annular friction surface designed to engage said friction member and rotate said wheel, and an annular depression adjacent said friction surface.

adapted to limit the transmission of power from the disk of the power wheel to said friction surface.

5. In a tile press of the character described, a power wheel provided with an annular friction surface imbedded in its periphery, a pair of rotating power disks for rotating said wheel in opposite directions, manually actuated means for moving one 10 of said power disks into engagement with the power wheel, automatically actuated means for moving the other disk into engagement with said power wheel, and a brake positioned in the line of travel of said 15 wheel for stopping the rotation thereof when the wheel reaches a predetermined point.

6. In a tile press of the character described, a pressing head, a screw member 20 for reciprocating said pressing head, a power wheel for rotating said screw member, said power wheel being positioned horizontally while the screw member is positioned vertically and reciprocates vertically, 25 a horizontally positioned power shaft extending across approximately the center of said power wheel, a pair of driving disks rigidly secured to said shaft on opposite sides of said power wheel and spaced apart 30 a sufficient distance to remain out of en-

gagement with said power wheel when in a certain position, spring actuated means for moving one of said wheels into engagement with said power wheel, and manually actuated means for reversing the action of 35 said spring actuated means and moving the opposite disk into engagement with said power wheel.

7. In a tile press of the character described, a driving shaft, a pair of driving 40 disks secured to said shaft, a pressing structure, and power means operated by said disks for moving said pressing structure into and out of operation, a pair of stops secured to said driving shaft, a sleeve rotatably mounted on said shaft between said stops, said sleeve having journal members extending therefrom, a fork member straddling part of said sleeve, said fork member having fork terminals straddling said journal members, a lever connected with said fork member, said lever being pivotally mounted at one end whereby as the lever is rocked the fork member will be moved for shifting said sleeve and said shaft longitudinally, a manually actuated rod for moving said lever, and oppositely acting 50 springs for moving said lever to a predetermined position.

CHARLES A. LANDBACK.
